UNITED STATES PATENT OFFICE.

JOHN F. BROWN, OF CHICAGO, ILLINOIS, ASSIGNOR TO ALBERT R. BAKER,
OF INDIANAPOLIS, INDIANA.

ORDER-HOLDER.

SPECIFICATION forming part of Letters Patent No. 430,169, dated June 17, 1890.

Application filed December 12, 1889. Serial No. 333,520. (No model.)

To all whom it may concern:

Be it known that I, JOHN F. BROWN, a citizen of the United States, residing at Chicago, in the county of Cook and State of Illinois, 5 have invented a new and useful Improvement in Order-Holders, of which the following is a specification.

This invention relates to the construction of what are known among stationers as "order-holders," the same being portfolios adapted to hold written orders for merchandise and be used by the clerk who puts up the goods for shipment or delivery while he is engaged in that duty. A patent already granted 10 to me, numbered 409,827, and dated August 27, 1889, shows another construction of these holders from that I now seek to patent, and will serve to give a general idea of the class of devices to which the invention relates.

20 In the accompanying drawings, I show at Figure 1 a plan, and at Fig. 2 an edge view, of my newly-devised holder. Fig. 3 is a partial edge view upon an enlarged scale. Fig. 4 is a partial edge view showing the manner 25 in which the holder is opened when orders are to be inserted or taken out. Figs. 5, 6, 7, and 8 are detail views of one of the narrow boards embodied in the holder.

My holder consists of two wide boards or 30 covers A A, two narrow boards B B, united to the covers A by flexible joints at *a*, and springs C C, acting as clamps upon the narrow boards, and also serving to hold said boards together, thereby dispensing with the 35 hinge heretofore usually employed to unite said boards. I also combine with the parts above mentioned a fulcrum-wire D, whose function is to serve as a fulcrum when the clamp is to be opened, and also to confine 40 the spring-clamps upon the boards.

The springs C have their side edges turned down, as shown at *c*, and such turned-down edges engage with the offset portions *b*, provided upon each of the narrow boards at that 45 portion of such boards which lies under the springs. This engagement by the lips *c* and offset *b* prevents any slipping of the springs backward, and they are held against slipping longitudinally by the end of the offset *b* in 50 one direction and by the fulcrum-wire in the

other direction, the ends of the fulcrum-wire being hooked over and inserted in recesses *d*, formed in those sides of the narrow boards which come together.

It will be noticed that I use two short 55 springs instead of a long one, as has heretofore been customary. My object in this is to attain strength and durability with a small amount of metal. There is a limit to the length of these flat springs, unless they be 60 made of such thin metal as to render them impracticable for this use.

The fulcrum device is capable of being turned upon its hooked ends until its body portion lies against the outside of one of the 65 short boards, when, by reversing the covers, as indicated at Fig. 4, and applying power to them, the clamping-springs will be opened sufficiently to allow the putting in or taking 70 out of the papers for which the holder is designed.

Each of the covers A and accompanying short board B are covered with canvas in the usual manner, such canvas forming the hinge *a*. It will be noticed that the fulcrum-wire 75 and the clamping-springs effectually protect the back corners of the holder, which are usually subjected to very severe wear and are apt to fray out and give way before other portions of the holder. The front corners 80 may be covered with leather or metal *e*, in the usual manner.

I claim—

1. The combination, with the covers of an order-holder, of clamping-springs C, having 85 their side edges turned inwardly to form lips *c* and engage with the boards to which they are applied, substantially as set forth.

2. In an order-holder, the combination of the covers A, narrow boards B, clamping- 90 springs C, having the inwardly-turned edges *c*, said boards B having the offsets *b* to engage with the spring-lips *c*, substantially as set forth.

3. In an order-holder, the short clamping- 95 springs C, in combination with a fulcrum-wire having its ends hooked over and confining said springs upon the holder, substantially as set forth.

4. In an order-holder having the boards B 100

B, the combination, with such boards, of a fulcrum-wire having hooked ends let into recesses *d* upon the abutting faces of the boards, and a clamping-spring, substantially as set forth.

5. In an order-holder, the sheet-metal clamping-springs *C*, located at the back corners, suitably secured in place and serving to cover and protect said corners, substantially as set forth.

6. In an order-holder, the clamping-springs *C*, having inward lips *c*, engaging with the boards, in combination with the fulcrum-wire having the bent-over ends, substantially as set forth.

JOHN F. BROWN.
